POWER CLOCK

Joseph Lato, Houston, Tex.

Application June 20, 1946, Serial No. 678,053

4 Claims. (Cl. 58—7)

1

This invention relates to new and useful improvements in a power clock for use in rotating and regulating a recording instrument and the like.

In oil well operations it is often desirable to record the pressure in the well at the various depths. To accomplish this, a pressure gauge and recording instrument is lowered into the well. A power clock is in operative connection with the revolving drum of such recording instrument and rotates said drum at a constant speed as the instrument is lowered through the various pressures of the well. With the power clocks in present use it has been found that in wells of varying depth it is desirable to use power clocks the speed of which is regulated to provide a constant speed in accordance with the depth of the well. This necessitates a different power clock for each depth of well, and in the case of deep wells, the type of power clock now in common use does not have sufficient power to continue operation throughout the entire length of time required to reach the full depth of the well. It is an object of this invention to provide a power clock of the character described having a variable speed control to permit use of the power clock in wells of varying depth.

It is another object of the invention to provide a power clock of the character described having a continuous operating life of twenty hours in contrast to the continuous operating life of the type of clock now in use which is approximately three hours.

Another object of the invention is to provide a novel means of controlling the energy of the power mechanism.

Another object of the invention is to provide a novel means of winding the main spring of the clock mechanism.

Another object of the invention is to provide a novel means for securing the drum of the recording instrument to the power clock.

The above and other objects will be apparent from the following description and illustrated in the accompanying drawings, wherein:

Figure 1 is a cross sectional front elevational view of the power clock showing the drum of the recording instrument attached.

Figure 2 is a side elevational view of the view shown in Figure 1.

Figure 3 is a cross sectional top view of the power transmitting means, taken on the line 3—3 of Figure 2, and

Figure 4 is an enlarged side view of the novel variable speed control mechanism taken on the line 4—4 of Figure 1 in cross section.

Referring now more particularly to the drawings, the numerals 1, 1 indicate a pair of side plates preferably composed of brass or similar rigid material. The side plates 1, 1 are secured

2

to a base 2 and the main spring housing 3 by means of suitable countersunk set screws 4. A main spring 5 is seated in said main spring housing 3 and is maintained in said housing by means of the plug 6. One end of said main spring is anchored to the side wall of said housing 3 and the other end thereof to the power shaft 7. The power shaft 7 extends through said plug 6 and housing 3 and has an annular shoulder 8 which bears against said main spring 5. One end of said shaft 7 is annularly reduced at 9 and bears outside threads on said annularly reduced portion to be received by suitable inside threads (not shown) in the drum 10 of the recording instrument. The end of said drum which is secured to the power clock has the annular reduced segmented outside threaded portion 11, the free end of said reduced portion being tapered inwardly. A nut 12 having inside threads to receive said outside threads of said reduced segmented portion of the drum, has the inside inwardly tapering wall 13 adapted to abut against said tapered free end of said portion 11. When the nut 12 has received the portion 11 of the drum 10 and is screwed tightly thereon, the inside tapering walls of the nut 12 will abut against the tapered end of the portion 11 and the segmented portion 11 will yield and will be tightly pressed against the shaft 7 and will securely grip the same.

The opposing end of the shaft 7 has the annularly reduced portion 14, said reduced portion extending through the end wall of the housing 3 and a portion thereof being externally threaded to receive the internal threads of the plug 15. Said reduced portion 14 of the shaft 9 terminates and is seated in the bridge 16. A coil spring 17 is loosely mounted on said shaft and abuts at one end against the plug 15, the plug 15 having an annularly reduced portion forming a shoulder to receive said coil spring and maintain same in position. The opposing end of said coil spring abuts against a clutch member 18 fixedly mounted on said shaft 7, one end of said clutch member having the annularly reduced portion forming a shoulder against which said spring 17 abuts. The opposing end of said clutch member having ratchet teeth adapted to mesh with the teeth of the opposing clutch member 19 which is mounted for free rotation on said shaft 7.

The outside wall of the clutch member 19 has suitable gear teeth which mesh with the gear teeth of the pinion gear 20, said gear 20 being fixedly mounted on the arbor 21, the ends of said arbor being annularly reduced and mounted for free rotation in the bridges 22, 23. Fixedly mounted on said arbor 21 and adapted to be rotated thereby is the worm gear 24 adapted to mesh with and rotate the worm 25 which is

fixedly mounted on the arbor 26. The ends of the arbor 26 are rotatably mounted in the side plates 1, 1. A gear 27 is fixedly mounted on said arbor 26 and is adapted to be rotated thereby. The gear teeth of said gear 26 are in mesh with the gear teeth of the pinion gear 28. The gear 28 is fixedly mounted on and rotates the arbor 29 and gear 30 which is also fixedly mounted on said arbor 29. The gear 30 is in mesh with the pinion gear 31, said gear 31 being fixedly mounted on and adapted to rotate the arbor 32. Mounted on and adapted to be rotated by the arbor 32 is a series of escapement wheels, the number of wheels and the number of teeth on each wheel varying, three wheels are shown in the drawings for illustration, the first wheel 33 having four teeth, the second wheel 34 having eight teeth and the third wheel 35 having sixteen teeth. An adjusting plate 36 is also mounted on said arbor 32. The wheel 33 is fixedly mounted on the arbor 32, and is adapted to be rotated thereby. The escapement wheel 33 has the axial sleeve 37 fixedly mounted thereon and extending laterally therefrom. The escapement wheel 34 has an axial sleeve 39 extending laterally from one side thereof, said sleeve being of slightly greater diameter than the sleeve 37 and adapted to be slidably mounted on said sleeve 37. The sleeve 39 has a spring 40 formed in said sleeve by cutting through three sides of a transverse strip in the wall of said sleeve. The escapement wheel 35 has an axial sleeve 41 extending laterally therefrom, said sleeve being of slightly greater diameter than the sleeve 39 and adapted to be slidably mounted thereon. A spring 42 is cut in said sleeve 41 as above described for the spring 40. The said sleeves 37, 39 are notched in the outside surface thereof as shown in Figure 4 of the drawings, which notches engage the spring of the opposing sleeve and tend to yieldably maintain the escapement wheels in the desired position. The adjusting plate 36 is fixedly attached to the sleeve 41. A pair of alignment bars 43, 43, fixedly mounted on the wheel 33, extend through suitable ports in the wheels 34, 35 and plate 36, and maintain the escapement wheels in alignment with each other.

When it is desired to operate the power clock at its fastest speed, the escapement wheels are permitted to remain in the position shown in Figure 4, with the pallet fork 44 in contact at one end with the escapement wheel 33 and in contact with the balance wheel 45 at the other end. The balance wheel 45 is axially mounted on the arbor 48. The hair spring 46 is anchored at one end to the stud 47 and at the other end to the arbor 48 and controls the balance wheel movement in the conventional manner. The arbor 48 is maintained in position by the usual bearings 50, 50.

To reduce the speed of the power clock, the adjusting plate 36 is manually moved laterally on the sleeve 37 towards the wheel 33, moving the wheels 35, 34 simultaneously along the axis of the arbor 32, the resistance of the spring 40 being overcome, moving the spring 40 out of the notch in the sleeve 37 but maintaining a gripping pressure on the sleeve 37. If only one degree of reduction is desired, the lateral movement is stopped as the wheel 34 abuts the wheel 33; and the teeth of the wheel 34 are in operating relation with the pallet fork 44, the increased number of teeth on the wheel 34 reducing the speed of the clock. If additional reduction of speed is desired, pressure may be applied manually on

the adjusting plate 36 overcoming the resistance of the spring 42, moving the spring 42 out of the notch in the sleeve 39 and permitting the adjusting plate 36 to move the wheel 35 laterally along the axis of the arbor 32 until the wheel 35 abuts the wheel 34 and the teeth of the wheel 35 are in operating relation with the pallet fork 44. To return the clock to its fastest speed, the plate 36 is manually moved laterally along the axis of the arbor 32 to its original position, carrying with it the wheel 35. As it is so moved the notch in the sleeve 39 engages the spring 42 in the sleeve 41 so that the sleeve 39 and wheel 34 are moved with the sleeve 41 until the notch in the sleeve 37 engages the spring 40, stopping the transverse movement of the wheel 34, leaving only the wheel 33 in contact with the pallet fork.

When the recording instrument is mounted on the power clock and it is desired to wind the main spring to set the clock in motion, the power clock will be held immovable by the operator and the drum 10 turned in a counterclockwise direction, the clutch member 18 permitting the shaft 7 to turn in a counterclockwise direction without operating the clock motor, but upon release of the drum by the operator, the spring 17 will move the clutch member 18 into engaged relation with the clutch member 19 and the clock motor will operate at the preselected speed, the clutch member 19 turning the gear 20 which in turn rotates the gear 24 which is in mesh with the worm 25 which rotates the arbor 26 and gear 27. The gear 27 is in mesh with and rotates the gear 28 which in turn rotates the arbor 29 and the pinion 30 which rotates the pinion gear 31 and arbor 32 upon which are mounted the variable speed escapement wheels 33, 34 and 35 which selectively contact the pallet fork 44 which is also in contact with the balance wheel 45 which is controlled by the hair spring 46.

The side plates 1, 1 have the cut away portions as at 48, 49, to permit ready access to the adjusting plate 36 when it is desired to alter the speed of the motor.

The embodiments of the invention herein shown and described are to be regarded as illustrative only and it is to be understood that the invention is susceptible to variation, modification and change within the scope of the appended claims.

What I claim is:

1. In a power clock of the character described having a framework, a main spring housing on said framework, a main spring anchored in said housing, a drive shaft extending through said housing and in operative connection with said main spring, a recording instrument drum to be rotated mounted on one end of said drive shaft, a train of gears in yieldable connection with the other end of said drive shaft, means for variably controlling the speed of the rotation of said drive shaft comprising an arbor adapted to be rotated by said train of gears, a series of escapement wheels having varied number of teeth and in axial alignment on said arbor, the first of said escapement wheels being fixedly mounted on said arbor and having an axial sleeve extending transversely therefrom and having a notch in said sleeve, the second of said escapement wheels having an axial sleeve extending transversely therefrom mounted on the sleeve of the first escapement wheel, a spring in said sleeve of said second escapement wheel adapted to be engaged by the notch in the sleeve of the first escapement wheel when the series of wheels are in extended position, said sleeve of said second escapement wheel hav-

ing a notch in the outer surface thereof, a third escapement wheel having an axial sleeve extending transversely therefrom, a spring in said sleeve of said third escapement wheel adapted to be engaged by the notch in said sleeve of said second escapement wheel when said series are in extended position, an adjusting plate fixedly connected to said sleeve of said third escapement wheel and in axial alignment with said series, alignment bars fixedly connected to said first escapement wheel and extending transversely therefrom, said second and third escapement wheels having ports therein through which said alignment bars extend and maintain said wheels and adjusting plate in alignment, a pallet fork adapted to be selectively engaged by said escapement wheels, a balance wheel in operative connection with said pallet fork, a hair spring controlling the movement of said balance wheel.

2. In a variable speed control for clock mechanisms comprising a drive mechanism, an arbor in operative connection with said drive mechanism, a series of escapement wheels mounted on said arbor, one of said wheels being anchored to said arbor, guide means mounted on said anchored wheel maintaining all of said series of wheels in alignment, said escapement wheels having a varied number of teeth thereon, a pallet fork adapted to contact said teeth when the various escapement wheels are moved into contacting position on the arbor.

3. In a variable speed control for clock mechanisms, a driving means, an arbor in connection with and adapted to be driven by said driving means, a series of escapement wheels mounted on and adapted to be rotated by said arbor, said escapement wheels having a varied number of spaced teeth thereon, each of said escapement

wheels having a lateral axial shaft upon which the adjoining wheel is slidably mounted, and means on said lateral axial shafts for releasably maintaining the adjoining wheels in their selected position, a pallet fork adapted to permit the arbor to rotate at the selected speed permitted by the escapement wheels moved into operative connection with said pallet fork.

4. In a variable speed control for clock mechanisms, a driving means, an arbor in connection with and adapted to be driven by said driving means, a series of escapement wheels mounted on and adapted to be rotated by said arbor, certain of said wheels being movable transversely and independently on said arbor and means for yieldingly maintaining each of said transversely movable wheels in the selected position on said arbor, a pallet fork adapted to permit the arbor to rotate at the selected speed permitted by the escapement wheels moved into operative connection with said pallet fork.
